UNITED STATES PATENT OFFICE.

JOHN SMITH, OF HOPEDALE, MASSACHUSETTS, ASSIGNOR TO DRAPER CORPORATION,
OF HOPEDALE, MASSACHUSETTS, A CORPORATION OF MAINE.

SHUTTLE.

1,273,794.

Specification of Letters Patent. Patented July 23, 1918.

Application filed January 18, 1918. Serial No. 212,510.

To all whom it may concern:

Be it known that I, JOHN SMITH, a citizen of the United States, residing at Hopedale, in the county of Worcester and State of Massachusetts, have invented an Improvement in Shuttles, of which the following description, in connection with the accompanying drawings, is a specification, like characters on the drawings representing like parts.

10 The invention to be hereinafter described relates to loom shuttles, and more particularly, though not necessarily, to loom shuttles employed in filling replenishing looms.

15 Loom shuttles are ordinarily provided with a side delivery eye through which the yarn or filling is drawn from the carrier or bobbin as the shuttle is picked. As the shuttle enters the shuttle-box it is subjected to a binding action between the front and rear walls

20 of the shuttle-box to assist in arresting and properly holding the shuttle, and the shuttle is quickly brought to rest.

During the flight of the shuttle, however, the yarn or filling is rapidly drawn through the side delivery eye and, as the shuttle is brought to rest at the end of its flight, the yarn or filling will frequently overrun and become slack between the shuttle and cloth selvage, notwithstanding the presence of 30 tension means within the shuttle itself. Under such conditions the yarn or filling is liable to and frequently does fail to be properly presented to the filling thread cutter ordinarily used in filling replenishing looms, 35 because, should the filling become slack between the cloth selvage and shuttle, it is liable to kink and take a wavy or irregular path between the shuttle and the cloth selvage where the filling thread cutter is to 40 act upon it.

An important feature of the present invention, therefore, consists of means on the exterior side wall of the shuttle to engage the yarn of filling delivered from the yarn 45 delivery eye as the shuttle enters the box and cause it to be pulled or straightened between the cloth selvage and shuttle. In carrying this feature of the invention into practical effect, the means for thus engaging and positioning the yarn or filling is secured to the shuttle, and extends over the outer surface of the side wall thereof near the delivery eye, said means being provided

with a surface adapted to retard free movement of the yarn when engaged therewith. 55

Another important feature of the invention consists in the yielding character of the yarn positioning means, whereby the yarn or filling may be pressed yieldingly against the side wall of the shuttle-box as the shuttle enters the box and drag upon the filling to straighten and position it with respect to the filling thread cutter. This characteristic of the invention may be variously contrived, but in the present instance the yarn 60 engaging means consists of some textile or other like material of yielding character mounted to extend transversely across the outer surface of the side wall of the shuttle-box preferably near or adjacent to the 65 side delivery eye.

The above and other features of the invention will be hereinafter more fully described in connection with the accompanying drawings showing one good, practical 75 embodiment of the invention.

Figure 1 is a perspective view of a shuttle having the present invention associated therewith;

Fig. 2 is a perspective view of the delivery eye end of the shuttle with the yarn positioning device and its securing means shown in separated relation; and

Fig. 3 is a sectional perspective view transversely of the shuttle-box showing the 85 action of the yarn positioning means upon the filling as the shuttle enters the box.

In the present illustration of the invention, the shuttle 1, Fig. 1, may be of the usual type employed in filling replenishing looms. The filling carrier 2 having the filling 3 wound thereon may be conveniently supported in the shuttle 1 by the usual bobbin-holding jaws 4. At the end of the shuttle remote from the bobbin-holding jaws 90 there is usually provided a shuttle-threading device which may be of any desired or preferred character as well understood by those skilled in the art. In the present instance of the invention, the threading device consists of a threading block 5 having a threading passage 6 whereby, after a filling has been replenished in the shuttle, the shuttle 100 may be automatically threaded as the shuttle is picked from the replenishing side of 105 the loom, all as common in the art.

The shuttle has a thread delivery eye 7 extending laterally with respect to the threading block 5 and through which the filling passes as the shuttle makes its excursions 5 across the lay. The threading eye 7 may be of usual character common in this type of shuttles.

In filling replenishing looms wherein prior to complete exhaustion of the filling 10 in the shuttle a new supply of filling is furnished, it is common to provide a thread parter or cutter between the cloth selvage and the shuttle-box to part or sever the filling leading from the filling carrier or bobbin 15 to be abandoned so that such filling end may be withdrawn with the outgoing filling carrier or bobbin and liability of its being interwoven with the cloth be avoided. Such thread parters or cutters are usually 20 supported to perform their parting or cutting functions at a predetermined point in a line extending between the fell of the cloth or cloth selvage and the shuttle when the latter is in the box at the filling replenishing 25 side of the loom. At such time the delivery eye 7 is usually at the leading end of the shuttle. In other words, when the shuttle is in the box at the filling replenishing side of the loom, the yarn or filling leading from 30 the side delivery eye of the shuttle extends substantially the full length of the shuttle between the side wall of the shuttle and the front wall of the shuttle-box, and as the shuttle is brought to rest, the unwinding 35 tendency of the filling drawn from the filling carrier or bobbin in the shuttle is liable to cause the filling to become slack or kinked between the selvage of the cloth and the delivery eye of the shuttle so that it will not 40 be in position to be parted or caught by the thread parter or cutter.

The present invention, therefore, contemplates means for acting upon the filling as it is delivered from the delivery eye of the 45 shuttle to straighten the filling as the shuttle enters the box at the filling replenishing side of the loom and thus position the filling for the action of the thread parter or cutter. This is best effected by disposing 50 on the outer side wall of the shuttle a yarn or filling-engaging device which will yieldingly press the filling against the side wall of the shuttle-box and obstruct free movement of the filling as the shuttle enters the 55 box.

In the present instance of the invention, the side wall of the shuttle is provided with a recess 8 back of the yarn delivery eye 7 in which is seated a support for the yarn- 60 engaging and positioning means. In the present instance of the invention the support comprises a plate 9, portions 10 of which are turned or bent to provide journals for a stud or pin 11 which extends 65 transversely of the outer side wall of the

shuttle. The stud or pin 11 is preferably covered by a material having a roughened or adhesive surface adapted to exert a retarding influence upon the yarn engaged by it, the term adhesive being used in the sense 70 of a clinging effect. In the present instance of the invention, the covering 12 is formed of textile material and either it or the pin 11 may be rotatable, or not, as desired. In order that the yarn engaging and position- 75 ing means may yieldingly act upon the yarn or filling as the shuttle enters the shuttlebox at the filling replenishing side of the loom, it is desirable that either the covering 12 be formed of sufficiently yielding ma- 80 terial to yieldingly press the yarn against the inner wall of the shuttle-box as the shuttle enters the same, or, that separate yielding means be provided to hold the yarn yieldingly against the wall of the shuttle- 85 box. In the present instance of the invention the support or plate 9 is preferably formed of spring metal and is secured to the countersunk portion at 8 of the side wall by means of a screw or other suitable hold- 90 ing means 13 which is adapted to pass through an opening 14 in the support or plate 9 and into the body of the shuttle.

It is usual in shuttles of the general character described to provide the side wall 15 95 of the shuttle with a longitudinal groove 16 through which the filling may extend when the shuttle is in the shuttle-box. The groove 16 is usually formed longitudinally of the shuttle in line with the side delivery eye 7. 100

The countersunk or recessed portion 8 formed in the side wall of the shuttle is somewhat enlarged at 17, Fig. 2, to accommodate the yarn-engaging and positioning means, and is sufficiently deep to permit the 105 yarn-engaging and positioning means to have a limited movement transversely relative to the side wall 15 of the shuttle.

The construction above described as one embodiment of the present invention is 110 found to be efficient and practical in obstructing the free movement of the yarn or filling by yieldingly pressing the same against the inner surface of the side wall 18 of the shuttle-box as the shuttle moves to 115 the end of its travel, the construction being such that the yarn or filling is straightened between the cloth selvage and the shuttle and properly positioned for the action of the thread parter or cutter. 120

The yarn-engaging and positioning means, it will be noted, is in the nature of a pad yieldingly supported upon the outer side wall of the shuttle back of the shuttle-eye, and acts upon the yarn or filling to properly 125 position it for the operation of the thread cutter by pressing the filling yieldingly against the wall of the shuttle-box as the shuttle moves to its final position of rest, at the end of its flight. 130

The lay 19 may, of course, be of any usual construction, and it, as well as the shuttle 1 may be provided with an opening for the passage of the filling carrier 2 when replenishment of filling is to be effected.

What is claimed is:

1. A shuttle having a yarn delivery eye adjacent one end thereof, and a yarn positioning device on the exterior side wall of the shuttle back of the yarn delivery eye to engage the yarn between the side wall of the shuttle and the wall of the shuttle-box as the shuttle enters the box.

2. A shuttle having a yarn delivery eye leading from the side of the shuttle, a device on the shuttle to engage the yarn between the side of the shuttle and the wall of the shuttle-box as the shuttle enters the box, and means for securing the device to the shuttle that it may act upon the yarn to press it against the inner wall of the shuttle-box.

3. A shuttle having a yarn delivery eye, means carried by the shuttle and acting upon the yarn back of the shuttle delivery eye to yieldingly press the yarn against the wall of the shuttle-box as the shuttle enters the box.

4. A shuttle having a delivery eye near one end thereof, a yarn engaging device extending transversely of the outer side wall of the shuttle back of the delivery eye, and a support for causing said device to press the yarn against the inner wall of the shuttle-box as the shuttle enters the box.

5. A shuttle having a delivery eye near one end thereof, a support secured to the outer side wall of the shuttle back of the delivery eye, and means sustained by said support to engage the yarn as the shuttle enters the shuttle-box and yieldingly press it against the wall of the shuttle-box to maintain the yarn taut between the shuttle and cloth selvage.

6. A shuttle having a delivery eye near one end and a groove extending longitudinally along the outer side wall of the shuttle from the delivery eye, and means extending transversely relative to said groove back of the delivery eye to engage and press the yarn

against the wall of the shuttle-box as the shuttle enters the box.

7. A shuttle having a yarn delivery eye near one end and a groove extending longitudinally along the outer side wall of the shuttle for the reception of the yarn as the shuttle enters the shuttle-box, and means located on the exterior side wall of the shuttle to engage the yarn and press it against the side wall of the shuttle-box as the shuttle moves in the box toward the outer end thereof.

8. A shuttle having a yarn delivery eye near one end, a pad mounted on the shuttle and extending from the outer side wall thereof back of the delivery eye, said pad having a surface to engage and press the yarn against the wall of the shuttle-box as the shuttle moves in the box toward the outer end thereof.

9. A shuttle having a yarn delivery eye near one end, a pad having a surface to engage and retard free movement of the yarn, and a support for said pad acting to press the yarn outwardly against the wall of the shuttle-box as the shuttle enters the box.

10. A shuttle having a yarn delivery eye, a pad having a surface to engage and retard free movement of the yarn, a plate secured to the outer side wall of the shuttle, means for securing the pad to the plate back of the yarn delivery eye, and means for causing the pad to yieldingly press against the yarn as the shuttle enters the shuttle-box to maintain the yarn taut between the cloth selvage and shuttle.

11. A shuttle having a delivery eye, a plate secured to the outer side wall of the shuttle, and a rotary pad carried by the plate back of the delivery eye and provided with a surface to engage and obstruct free movement of the yarn that it may be straightened between the shuttle and cloth selvage as the shuttle enters the box.

In testimony whereof, I have signed my name to this specification.

JOHN SMITH.
